UNITED STATES PATENT OFFICE.

SOLOMON RIPPE, OF LITTLE ROCK, ARKANSAS.

COLLAR-BUTTON.

1,218,318.

Specification of Letters Patent.

Patented Mar. 6, 1917.

Application filed October 27, 1916. Serial No. 128,023.

To all whom it may concern:

Be it known that I, SOLOMON RIPPE, a citizen of the United States, residing at Little Rock, in the county of Pulaski and State of Arkansas, have invented certain new and useful Improvements in Collar-Buttons, of which the following is a specification.

This invention relates to a collar button designed expressly to secure the back of a collar of the rolled over type to the back of the neck band, the object of the invention being the easy drawal of the necktie through the collar.

Much of the difficulty in drawing ties through collars of this type is due to their catching on the head of the button or being pressed by the button head into close frictional contact with the collar, the button head acting practically as a friction brake on the tie. This is entirely avoided in the type of button invented by me.

In the accompanying drawings,

Figure 1 is a face elevation of one of the buttons in position, an outer member of the collar and the tie being broken away.

Fig. 2 is a section on the line 2—2 of Fig. 1.

Fig. 3 is a face or plan view of the button.

Fig. 4 is a section on the line 4—4 of Fig. 3.

In constructing the button I employ a rectangular frame 1 and within said frame and arranged centrally along its major axis is a roller 2. Midway the ends of the frame and on its inner face the side members are connected by a yoke 3 which carries a but-

ton 4. Prongs 5 are carried by the frame on said inner face.

My button is placed in position the reverse of that usually occupied by collar buttons. In Figs. 1 and 2 A is the outer member of the collar, B the inner member having the button hole, C the shirt neckband, and D the tie.

The button is placed in the collar first, and then the tie placed in position extending transverse to and across the roller 2. The collar is then put on, the button head 4 being inserted in the usual button hole of the neck band C.

The button is placed with its long axis vertical, or transverse to the tie, and is held from turning by the prongs 5 penetrating the collar member B and neck band, but terminating at and not passing through the latter.

As the tie rides on the roller 2 it will draw easily through the collar.

What I claim is:—

1. A button comprising an oblong frame, a roller mounted in the frame and on the line of its major axis, a yoke carried midway the ends of the frame and on its inner face, a button carried by the yoke, and prongs carried by said inner face of the frame.

2. A collar button comprising a rectangular frame, a roller arranged on the longitudinal axis of the frame, a yoke at right angles to and straddling said roller, and a button head carried by the yoke.

In testimony whereof I affix my signature.

SOLOMON RIPPE.
